UNITED STATES PATENT OFFICE.

JOHN J. DOUGHERTY, OF SCRANTON, PENNSYLVANIA, ASSIGNOR OF ONE-HALF TO
WILLIAM P. BOLAND, OF SCRANTON, PENNSYLVANIA.

DUMPING APPLIANCE.

Application filed October 13, 1923. Serial No. 668,451.

This invention comprises a dumping appliance. It is especially useful in connection with so-called automatic dumping cars and the like wherein the cars are elevated and tilted to unload the contents of the car through a swinging door placed generally, in an end of the car.

It is contemplated among the objects of the invention to provide a temporary locking instrumentality which will be effective to hold the door closed when the regular locking device has been unlocked and at the same time automatically release and permit dumping of the contents of the car when tilted in the unloading operation.

Another object is the elimination of heavy and cumbersome latches, bars, hooks and the like which generally require hammering or actuation with a bar, and are, for the most part, very difficult to operate; to simplify and reduce the number of parts and to generally provide an efficient device for the purposes set forth.

A drawing illustrating an embodiment of the invention is hereto attached, the following views being shown:

Figure 1, is a view in side elevation showing an embodiment of the invention in connection with a car, the parts being shown in closed position and the permanent lock being released just prior to dumping.

Fig. 2, is a view in vertical section on line 2—2 of Fig. 1;

Fig. 3, is a view in end elevation, of a slightly modified form and looking at the front end of the car;

Fig. 4, is a fragmentary detail view in perspective of a portion of the device.

In these views, 1 designates a car body having a door 2, swingingly mounted at its upper edge on one end of the car, the other end 3, being an integral portion of the body. The door 2, is provided with keepers 4, extending outwardly beyond the plane of the sides of the car and adapted to be embraced by and securely locked with a unitary loop-shaped locking-member 5, which member is pivotally and slidably mounted so that it may be brought into position to engage the keeper 4, and then swung down to lock the parts together, the weight of a portion of the latch acting to maintain the parts locked until operated by simply turning up the loop and moving it back from the lug. This

loop-shaped locking member 5 forms the subject matter of a separate application, filed Oct. 13, 1923, Serial No. 668,450. In Fig. 1, the parts are shown in unlocked position just prior to the act of dumping, the position of the parts when locked being indicated in dotted lines.

Suitably attached to the door, as by links 6 and an eye 7, is a connecting bar or link 8 disposed on the outside of the car body. This is carried to approximately the other end of the car, where it is connected with a depending arm 9. The arm 9, is connected with and mounted for swinging movement on a cross bar 10, pivotally mounted in bearings 11, placed at opposite sides of the car body, and provided, intermediate these points with an enlarged depending bail or lever portion 12. In the form shown in Fig. 2, this is in the shape of a loop of substantial area and is intended to be engaged by and held against the inside of the front end of the car by the contents of the body. In other words, when the body is filled up above the lower portion of the bail, the bail will bear against and be held in engagement with the inside of the front of the car, and will, through link 8 and its connection with the swinging door, hold the door in closed position until the car is tilted in the dumping operation. The tilting will remove the contents from the bail and permit the outward swinging of the door on its hinges. The device constitutes a very simple and effective means of permitting dumping at the same time maintaining the door in closed position until the car has been actually tilted.

In the form shown in Figs. 3 and 4, there is a slightly modified bail construction wherein a hook 13 is substituted for the looped bail shown in Fig. 2, the hooked portion being adapted to pass through an opening 14 in the front of the car and be engaged by a latch 15, pivotally mounted on a plate 16 secured to the front of the car. This provides a simple and efficient auxiliary locking device or one which may be used independently of the looped member 12 previously described.

While the invention has been described in connection with the present embodiment, it will be understood that I do not wish to be limited to the precise form of this disclosure, as many changes in the structure and ar-

angement of the parts are considered within the scope of the invention as set forth in the claims.

What I claim is:

- 5 1. A dumping appliance comprising a body; a door mounted for swinging movement thereon; instrumentality disposed on the exterior of the body and connected with the door and including a downwardly-extending member within the body and adapted to bear against the inside of the front end of the car and be engaged by contents of the body to maintain the door in closed position.
- 10 2. A dumping appliance comprising a body; a door mounted for swinging movement thereon; instrumentality disposed on the exterior of the body and connected with the door and including a downwardly-extending member within the body and adapted to bear against the inside of the front end of the car and be engaged by contents of the body to maintain the door in closed position, and means associated with the door
- 15 3. A dumping appliance comprising a body; a door mounted for swinging movement thereon; instrumentality disposed on the exterior of the body and connected with the door and including a downwardly-extending member within the body and adapted to bear against the inside of the front end of the car and be engaged by contents of the body to maintain the door in closed position, and means associated with the door
- 20 4. A dumping appliance comprising a body; a door mounted for swinging movement thereon; instrumentality connected with the door and including a member adapted to be engaged by contents of the body to maintain the door in closed position, means for locking the contents-engaging member to a portion of the body, said means including a bail provided with a hook adapted to pass through an opening provided in a portion of the body; and a locking member operatively associated therewith.
- 25 5. A dumping appliance comprising a body; a door swingingly mounted thereon; a member attached to one end of the door and extending into proximity to the other end of the body opposite the door; an arm connected with the member; a cross-bar attached to the arm and on which the arm is pivotally mounted; a bail on the cross-bar adapted to actuate the arm, said bail being adapted to be engaged by contents of the body and through the instrumentality of the arm and connecting member, to hold the door in closed position until the car is tilted.

end of the car and be engaged by contents of the body to maintain the door in closed position, and means for locking the contents-engaging member to a portion of the body.

4. A dumping appliance comprising a body; a door mounted for swinging movement thereon; instrumentality connected with the door and including a member adapted to be engaged by contents of the body to maintain the door in closed position, means for locking the contents-engaging member to a portion of the body, said means including a bail provided with a hook adapted to pass through an opening provided in a portion of the body; and a locking member operatively associated therewith.

5. A dumping appliance comprising a body; a door swingingly mounted thereon; a member attached to one end of the door and extending into proximity to the other end of the body opposite the door; an arm connected with the member; a cross-bar attached to the arm and on which the arm is pivotally mounted; a bail on the cross-bar adapted to actuate the arm, said bail being adapted to be engaged by contents of the body and through the instrumentality of the arm and connecting member, to hold the door in closed position until the car is tilted.

In testimony whereof I affix my signature.
JOHN J. DOUGHERTY.
